HAIR DRIER

Royal McShea, Medicine Lodge, Kan.

Application December 9, 1935, Serial No. 53,670

1 Claim. (Cl. 34—26)

This invention relates to a hair drier and is especially adapted for use by hairdressing establishments, and has for the primary object the provision of a device of this character which will deliver to a person's hair air filtered of foreign matter with the moisture content thereof reduced to a minimum and of a temperature which will be comfortable to a person so that the hair may be dried rapidly and thoroughly without discomfort to the person.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a vertical sectional view illustrating a hair drier constructed in accordance with my invention.

Figure 2 is a sectional view taken on the line 2—2 of Figure 1.

Referring in detail to the drawing, the numeral 1 indicates a casing divided into chambers 2 and 3. A fan 4 of any desired character is mounted in the chamber 3, the outlet of which is indicated by the character 5 and extends into the chamber 2 so that air is taken from the chamber 3 and forced into the chamber 2 and escapes therefrom by a pipe 6. A flexible hose 7 is connected to the pipe 6 and has connected thereto a hood or nozzle 8 capable of fitting over a person's head. A damper or valve 9 is located in the pipe 6 and may be adjusted for regulating the flow of air from the chamber 2 to the hood 8. A vent pipe 10 communicates with the chamber 2 and with the atmosphere and has a gate valve 11 which may be readily adjusted into open and closed position.

Carried by the hood 8 and of a shape similar to the latter is a casing 12 defining between itself and the hood 8 an air passage 13 having an outlet nipple 14 to which is connected a flexible pipe 15. The other end of the flexible pipe is connected to a hood 16 arranged in communication with the chamber 3. A filter 17 is placed between the hood 16 and the interior of the chamber 3. The hood also is equipped with a gate valve 18 which may be opened to establish communication between the atmosphere and the interior of the hood 16. The filter 17 may be of any desired construction and of any suitable material. The casing 12 projects slightly beyond the discharge opening of the hood 8 so that the treated air delivered onto

a person's head may pass therefrom through the passage 13 and pipe 15 to the chamber 3 by the suction of the fan 4. The air on passing into the chamber 3 is filtered so that foreign matter is removed therefrom before being expelled into the chamber 2.

Arranged in the chamber 2 is an absorbent bed 19 for the air to contact with during movement to the chamber 2 from the chamber 3 to the pipe 6. Any desired material may be employed in the construction of the absorbent bed which acts to remove from the air moisture so that the air delivered to the person's head by the hood 8 will have its moisture content lowered to a minimum.

A cooling coil 20 is located in the pipe 6 over which the air from the chamber 2 must pass on its way to the hood 8. The cooling coil acts to lower the temperature of the air and it is preferable that this air be of a temperature of substantially blood heat so that the air contacting the head of the person will be of substantially the same temperature as of the person to free the person of discomfort either from air of too high or too low a temperature. The air also having its moisture content reduced to a minimum by the absorbing bed 19 will more thoroughly and quickly dry the hair of a person.

A cooling coil 21 may be arranged in the absorbent bed 19 for the purpose of lowering its temperature. The cooling coils 20 and 21 may be cooled in any well known manner.

After the device has been in use for a period of time, the absorbent bed must be freed of the moisture collected and to accomplish this a heating device 22 of any desired construction is arranged in the chamber 2 and may or may not be thermostatically controlled and automatically lighted or extinguished. The heating device will rapidly dry the absorbent bed of moisture and during this operation the gate valve 9 is closed and the gate valve 11 is opened so that the drying air may pass to the atmosphere.

During the use of the device for the purpose of drying hair should it be desirable to obtain air to the chamber 3 directly from the atmosphere, the gate valve 18 may be opened.

Having described the invention, I claim:

A hair drier comprising a casing having a vertically arranged chamber and a fan chamber connecting with the lower end of the vertical chamber, said vertical chamber having opposed outlets adjacent the upper ends thereof, valves for controlling said outlets, a head engaging means connected to one of said outlets, means connecting said head engaging means to the fan chamber,

a fan operating in the fan chamber for forcing air through the vertical chamber to said head engaging means, a heating means located between the fan chamber and the vertical chamber and 5 contacted by the air from the fan, spaced absorbent beds arranged endwise of the vertical

chamber and each including connected parallel portions to intercept the air passing through the vertical chamber, and cooling coils extending substantially the full lengths of the absorbent beds and embedded therein.

ROYAL McSHEA.
